UNITED STATES PATENT OFFICE.

FRANCIS E. MATTHEWS, OF GLOUSTER, OHIO, ASSIGNOR OF ONE-HALF TO
GEORGE E. FAIRES, OF SAME PLACE.

COMBINED SCRUBBING-BRUSH AND MOP HOLDER.

SPECIFICATION forming part of Letters Patent No. 586,857, dated July 20, 1897.

Application filed March 27, 1897. Serial No. 629,558. (No model.)

To all whom it may concern:

Be it known that I, FRANCIS E. MATTHEWS, a citizen of the United States, and a resident of Gloucester, in the county of Athens and State 5 of Ohio, have invented certain new and useful Improvements in a Combined Scrubbing-Brush and Mop Holder; and I do hereby declare that the following is a full, clear, and exact description of the invention, which will 10 enable others skilled in the art to which it appertains to make and use the same, reference being had to the accompanying drawings, which form a part of this specification.

My invention relates to a combined scrubbing-brush and mop holder, and its object is 15 to provide an improved construction of the same by which the holder can be connected with a scrubbing brush or rubber and be readily disconnected therefrom and be engaged with a mop, sponge, or other similar article.

The invention consists, essentially, in a holder consisting of a spring-metal rod bent over at its center to form a loop and forming 20 two spring-arms the ends of which are curved backwardly and then bent outwardly at right angles and pointed and adapted to engage with eyes secured to a scrubbing-brush or to penetrate a mop, in combination with a slide 25 encircling said arms and a handle passing through said loop and secured to the slide, as hereinafter fully described and claimed.

In the accompanying drawings, Figure 1 is 30 a perspective view showing my improved holder connected with a scrubbing-brush. Fig. 2 is a plan view, the brush being removed and the holder connected with a mop. Fig. 3 is a side view.

In the said drawings, the reference-numeral 10 designates the holder, consisting of a spring-metal bar bent at its center to form a loop or coil 2 and two arms 3. The ends of these arms are curved backwardly, forming short arms 4, the extremities of which are bent outwardly at approximately right angles to the 15 arms 1 and sharpened, forming pointed lugs 5.

The numeral 6 designates a slide, consisting of an oblong ring which encircles the arms 3 and is secured to a handle 7, which passes through the loop 2.

50

The numeral 8 designates a scrubbing-brush provided with screw-eyes 9, with which the lugs 5 are adapted to engage.

The numeral 10 designates a mop with which the pointed lugs engage when the device is employed as a mop-holder.

In practice when the device is to be used as a brush-holder the slide 6 is pushed toward the ends of the holder by means of the handle, contracting the arms 3, so that the lugs 60 6 can pass between the screw-eyes of the brush. The slide is then moved in a reverse direction, when the arms through their resiliency will spring outwardly and the lugs will pass through the eyes, thus connecting 65 the brush with the holder.

When used as a mop-holder, the arms are contracted, as before described, withdrawing the lugs from the eyes, so as to disengage the brush from the holder. A mop or cloth is 70 then applied to the ends of the holder and the arms allowed to expand, when the pointed lugs will pierce the same and thereby securely hold it in place.

Having thus fully described my invention, 75 what I claim is—

The combination with the handle, of the holder consisting of a spring-metal rod bent at the center into a coil or loop, through which said handle passes, forming two expanded spring-arms, the ends of which are bent outwardly at approximately right angles to said arms and the extremities pointed, and the slide embracing said arms and movable thereon, substantially as described.

85

In testimony that I claim the foregoing as my own I have hereunto affixed my signature in presence of two witnesses.

FRANCIS E. MATTHEWS.
